United States Patent Office

Des. 191,883
Patented Dec. 5, 1961

191,883

NUT

George S. Wing, Palos Verdes Estates, Calif., assignor to
Hi-Shear Rivet Tool Company, Torrance, Calif., a cor-
poration of California

Filed Feb. 10, 1958, Ser. No. 49,585

Term of patent 14 years

(Cl. D54—9)

Fig. 1.

Fig. 2.

Fig. 3.

FIG. 1 is a side elevation of a nut showing my new design, the back side elevation being identical; and

FIGS. 2 and 3 are right hand and left hand end views respectively of the nut shown in FIG. 1.

I claim:

The ornamental design for a nut, as shown and de-
scribed.
